UNITED STATES PATENT OFFICE

WILLIAM E. WELLS, OF BIRDSEYE, INDIANA

NUT

Application filed January 2, 1930. Serial No. 413,068.

This invention relates generally to the class of hardware, and has particular reference to an improved nut for threadedly engaging a threaded stem, bolt, spindle or the like.

As an object, the invention comprehends an improved nut which is constructed in such a manner as to be engaged by a wrench with greater facility and more security than ordinary types of nuts that are now in general use and on the market.

The invention further aims to provide a nut which may be turned by a wrench while imparting lesser strains and stresses to the wrench and in which the nut may be disposed in closer proximity to a wall or corner of a structure than the usual type of nuts.

More specifically, the invention contemplates a nut having non-parallel side faces and truncated apexes at the juncture of said side faces, which truncated apexes are formed with wrench jaw receiving recesses within which at least two of said recesses, the wrench jaws preferably engage for turning the nut.

Other objects of the invention reside in the comparative simplicity of construction and mode of use of the nut, the economy with which it may be produced and the general efficiency derived therefrom.

With the above recited and other objects in view, reference is had to the following description and accompanying drawing, in which there is exhibited one example or embodiment of the invention, while the claims define the actual scope of the same.

In the drawing:

Figure 1 is a plan view of a nut constructed in accordance with the invention.

Figure 2 is a side view thereof.

Figure 3 is a cross sectional view therethrough taken approximately on the line indicated at 3-3 in Figure 1.

Referring to the drawing by characters of reference, the nut consists of a body 5 which is provided with a plurality of major side faces 6 disposed in non-parallel relation and at an angle to each other. Preferably, the nut is in the form of an equilateral triangle as illustrated, although it is to be understood

that it is not necessarily restricted to this shape. The nut body 5 is formed with truncated apexes 7 which present minor side faces disposed parallel to and opposite the major faces of the nut, and said truncated apexes 7 are formed with wrench jaw receiving recesses or notches 8 which preferably exceed a semi-circle and which are designed to receive the similarly formed jaws of a wrench. In practice, at least two of said recesses will preferably receive a pair of wrench jaws for the purpose of turning the nut and, consequently, the wrench shank proper will engage with one of the major side faces 6 whereby a free point engagement is established at a point at one side of the axis of rotation of the nut, thus securely establishing a connection between the wrench and the nut and subjecting the wrench to lesser strain or stress than is produced on a wrench with the ordinary types of nuts. It will be further apparent that due to the shape of the nut, it may be installed on a bolt or threaded stem which is set closer to a wall, corner or angle of a structure. It is further apparent that the notches or recesses 8 which extend completely throughout the depth or thickness of the nut, may be employed to receive therethrough a pin screw or other device anchored in a stationary structure which will serve to lock the nut against retrograde movement.

What is claimed is:

1. As a new article of manufacture, a nut having non-parallel side faces and truncated apexes at the juncture of the side faces, said truncated apexes having wrench receiving recesses.

2. As a new article of manufacture, a nut having non-parallel side faces and truncated apexes at the juncture of the side faces, said truncated apexes having wrench receiving recesses extending throughout the thickness of the nut.

3. As a new article of manufacture, a nut in the form of an equilateral triangle having truncated apexes provided with wrench receiving recesses.

4. As a new article of manufacture, a nut in the form of an equilateral triangle hav-

ing truncated apexes provided with wrench receiving recesses exceeding a semi-circle.

5. As a new article of manufacture, a nut in the form of an equilateral triangle having truncated apexes presenting minor faces parallel to the opposite major faces of the nut, said minor faces provided with wrench receiving recesses.

WILLIAM E. WELLS.
